SCALE

Filed May 19, 1926

INVENTOR.

Louis Jaenichen,
BY Francis D. Hardecky

ATTORNEY.

UNITED STATES PATENT OFFICE

LOUIS JAENICHEN, OF SPRINGFIELD TOWNSHIP, OAKLAND COUNTY, MICHIGAN, AS
SIGNOR TO THE STANDARD COMPUTING SCALE COMPANY, OF DETROIT, MICHIGAN,
A CORPORATION OF MICHIGAN

SCALE

Application filed May 19, 1926. Serial No. 110,162.

The present invention relates to scales and particularly to computing platform scales.

Heretofore computing platform scales of the compound lever type have been more or less inaccurate due to the difficulty of so constructing the scale that the platform in its movement under the load would remain parallel to itself. This has been neutralized in one known type of scale by so constructing the levers, springs etc., that the platform has very little movement and the indicator pinion accordingly made very small. Such a construction is open to the objection that the parts must be very accurately made and some 15 of the parts consequently more or less delicate.

The present invention has among its objects to overcome these objections and provide a scale of this type in which the platform may 20 have a considerable movement and remain substantially parallel to itself throughout and consequently the indicator parts may be made sufficiently large to stand rough usage and not require extremely accurate workmanship, yet 25 the scale will be accurate in its operation.

Other objects will readily appear to those skilled in the art upon reference to the following description and drawing in which—

Fig. 1 is a side elevation of the working 30 parts of the scale.

Fig. 2 is an end elevation thereof from the right of Fig. 1.

Fig. 3 is a diagrammatic illustration of the action of certain parts of the mechanism.

35 In the drawings, the lever housing is shown at 10 with an upright casing 11 at one end thereof.

The platform 12 is provided with legs 13 and 14 extending down into the housing 10 40 and resting on the main levers 15 and secondary levers 16 respective. The main levers 15 are pivoted upon the arms 17 secured to housing 10 and extend to the rear of the latter to a point under casing 11 where their face ends 45 are supported by springs 18. The latter extend upward into the casing 11 and are attached at their upper ends to an equalizing bar 19 supported pivotally upon an adjustable stud 20 carried in an arm 21 forming part of 50 casing 11. Springs 18 are connected to main

levers 15 close to the ends of the latter through suitable knife edge pivots 22.

Secondary levers 16 are supported, by means of suitable knife edge pivots 25, at 55 one end by the main levers 15 through links 26 and at their other ends by links 27 which latter extend up through casing 11 to near the extreme upper end thereof where they are provided with eyes 28 adapted to hook over the hooks 29 formed within the casing 60 head.

The extreme end of one of the levers 15 has secured thereto a rod 35 provided at its upper end with a rack 36 adapted to coact with a pinion 37 carried upon a rotatable 65 shaft 38 to which is secured a pointer 39 in front of a dial 40 provided with suitable indications.

In the operation of the scale, it should be noted that, as the legs 13 and 14 are fixed 70 rigidly to the platform 12, and, as leg 13 on its pivot moves on the arc of a circle having its center at the pivot on arm 17, the lower end of leg 14 must move laterally a short distance with leg 13. Consequently, lever 16 75 must move longitudinally whenever the platform 12 moves vertically. For this reason, lever 16 must be supported on links permitting such movement.

However, in scales of this type as usually 80 constructed, lever 16 is supported upon two links of about the length of link 26, the one at the rear end of the lever being swung from the housing. This arrangement, on account of the angular movement of the latter link 85 and its short radius, say for example about two inches, causes an upward movement of its end of lever 16, thereby opposing the downward movement of the platform. This action therefore seriously interferes with the accuracy of the scale. It also tends to bind the pivot.

In the present construction, link 27 is constructed of such length that the arc through 90 which its lower end swings is so flat as to be 95 to intents and purposes a horizontal line and the downward movement of platform 12 is not opposed to any noticeable degree by the relative upward movement of lever 16.

The arcs referred to are shown in compari- 100

son in Fig. 3. In this figure the arc A represents the travel of the lower end of the known link and the arc B that of link 27. These arcs are somewhat longer than those actually travelled but it will be noted that while the vertical distance of the ends of arc B from a true horizontal line is hardly detectable, the vertical distance of the ends of arc A from the horizontal is approximately an eighth of an inch.

10 Now having described the invention and the preferred form of embodiment thereof it is to be noted that the said invention is not to be limited to the specific details herein set forth but only by the scope of the claims which follow.

I claim:—

1. In a compound lever platform scale having an upright casing at one end of the platform housing, a main lever, a secondary lever supported at one end upon said main lever and at its other end by a link extending up into and supported by said upright casing.

2. In a compound lever platform scale having an upright casing at one end of the platform housing, a main lever, and a secondary lever supporting the platform, said secondary lever being supported at one end by said main lever, and means for supporting the other end of said secondary lever said means being of sufficient length and so arranged as to permit longitudinal movement of said secondary lever in a substantially horizontal path.

3. In a compound lever platform scale having an upright casing at one end of the platform housing, a main lever, and a secondary lever supporting the platform, said secondary lever being supported at one end by said main lever, and means for supporting the other end of said secondary lever said means being adapted to permit longitudinal movement of said secondary lever in a substantially horizontal path, said means consisting of a link pivotally connected to said secondary lever and supported from the top of said upright casing.

LOUIS JAENICHEN.
